ATTACHED CLOSURE FOR CONTAINERS

Willi Gräbner, Zell on the Mosel, Germany, assignor to Dr. Lucas & Co., Zell on the Mosel, Germany

Application October 18, 1950, Serial No. 190,772
In Germany October 31, 1949

4 Claims. (Cl. 220—30.5)

1

This invention relates to a nonremovable closure for tubes, bottles and similar containers.

Closures, especially for tubes, are generally constructed in such a way that the closing cap when unscrewed from the body of the tube forms a separate member no longer connected with the container. Owing to this arrangement closing caps are easily lost with the result that the contents of the tubes cannot be fully utilized.

It is the object of the invention to overcome this defect by the construction of a closure whose closing cap is not separated from the tube after the opening of the latter and thus cannot get lost. Attached closures for tubes, bottles and the like are of course known to the art. One of them has a closing screw consisting of one part and provided with two connecting flaps reaching to the tube and exposing between them the thread of the mouth of the tube, and radially inwardly projecting folds at the lower ends of the flaps grasp special ears disposed on the mouth of the container. After opening of the tube and exposure of the mouth thereof the closures can be turned over, the projections on the extended flaps preventing them from falling off.

Other known tube closures comprise two parts, one of which is a closing cap to be screwed on above and the other a lower threaded ring surrounding the thread of the mouth. Both parts are connected by a joint and have to be jointly screwed up and down. When the closing member has been screwed up high enough, the upper part can be turned down.

Both kinds of closures are open to serious objections. Above all, they not only fail to cover the thread but expose essential parts thereof. The thread of a tube in use is more or less soiled by the contents, and this has the effect that closures of the kind mentioned could not be utilized any longer. Furthermore, in both known constructions the actual mouth must necessarily be very long, so that the closure members are expensive to produce.

In contradistinction to these known closures the closure according to the invention covers the mouth of the container down to the shoulder of the tube, so that the latter cannot be rendered useless by its contents. For this reason, the closing cap, by means of a bayonet closure, overlaps a counterpart disposed on the mouth of the tube, one half of the bayonet closure being constructed to form a joint.

When the cap is turned in closing direction the arrangement acts as a two-part bayonet closure. In opening position, however, the bayonet closure

can be released only on one side, the other part thereof, owing to its construction as a joint, holding the closing cap. About this joint the closing cap can be brought into opening position. To prevent the entire arrangement from being removable or turnable the counterpart for the closing cap is nonremovably secured on the mouth of the container. One of the guides of the counterpart cooperates with a bayonet cam formed on the closing cap; the other guide is not interrupted, so that it forms a joint with its associated second cam of the closing cap. This joint cooperates in carrying out the rotary motion of the cap for both opening and closing.

The two guides on the counterpart on which the cams of the cap slide along are helically formed in known manner, so that during the closing operation some tightening of the cap in axial direction to the tube occurs. The opening motion and thereby the positioning of the cap for opening is limited by a stop which thus fixes also the opening position of the cap at which the front part of the bayonet closure can be brought into opening position, so that the cap tilts upwardly and rearwardly and exposes the outlet opening of the tube.

The counterpart to the closing cap may be fastened to the mouth of the container in any desired manner. The upper edge of the mouth of the container may be advantageously flanged across the counterpart of the closing cap, in which case the inner surface of the cap, possibly with an interposed packing, directly cooperates with this flanged upper edge of the mouth of the tube.

This arrangement can be applied also to other containers, as bottles and the like. The closure can be made from any suitable material.

One embodiment of the invention is illustrated in the accompanying drawings, in which

Figure 1 is an external view of a tube fitted with the closure according to the invention;

Fig. 2, a top view thereof;

Fig. 3, a perspective view of the appliance when opened;

Fig. 4, a vertical section of the closure with the closing cap brought into opening position;

Fig. 5, a view of the same arrangement shown in Fig. 4 but with the cap turned over;

Fig. 6, a section of the arrangement when the closing cap is brought into closing position, i. e., after the cap has been turned 90° in closing direction;

Fig. 7, a front view of the holding member for the closing cap;

Fig. 8, a top view of the holding member;
Fig. 9, a bottom view of the holding member;
and

Fig. 10, an internal view of the closing cap.

Referring to the drawing, 1 is the container provided with the neck portion 2 over which the annular holding member 3 is placed already during the manufacturing process and suitably secured against removal and rotation. The upper edge 2a may for instance be flanged.

The closure cap 4 has the shape shown in the drawings, that is, it is fitted with two inwardly and upwardly projecting bayonet lugs 5. The rear bayonet lug 5 is so constructed to form an abutment 6 with which the cap 4 in the open position according to Fig. 5 engages the surface of the tube.

The holding member 3 is firmly and nonrotatably arranged on the mouth 2 of the tube and possesses two grooves 7 and 8 extending in the direction of rotation corresponding to the closing operation, that is, spirally downwardly. In these grooves 7 and 8 slide the lugs 5 of the closing cap 4. Within the cut-out 9 of the holding member 3 the grooves are interrupted to enable one lug 5a of the cap 4 to pass out of the holding member 3 and thus permit opening of the cap. As indicated in Fig. 9, the other lug 5b of the cap cannot get out of the groove 8 when the lug 5a registers with cut-out 9. Thus, the rear lug 5b and the groove 8 form the joint.

The operation is as follows:

When the closing cap 4 is in the position shown in Fig. 4 the front lug 5a has left its groove 7, and the cap 4 can then be pivoted about lug 5b into the opening position according to Figs. 3 and 5. The groove portion 8 increases in depth away from the cut-out 9, while the groove portion 7 decreases in depth away from the cut-out 9 so that a stop face 8a is formed where the groove portion 7, 8 meet. This stop face renders the position for the opening of the cap 4 perceptible. Having been closed, the cap 4 is turned about 90° in the direction of a screw cap provided with right handed thread, and during this operation the front lug 5a enters the groove 7. As the guides 7 and 8 ascend in helical fashion towards the tube, the cap 4, by means of these grooves 7 and 8 and the lugs 5a, 5b, is simultaneously tightened in axial direction towards the tube, so that the inner surface of the cap 4 comes closer to the flanging or beading 2a. Between this surface and the flanging 2a a packing may be interposed in known manner. The closure is assembled by placing members 3, 4 in the position of Fig. 5 on the neck portion 2 of the container, and thereupon forming the flange 2a in a suitable manner.

I claim:

1. A closure comprising in combination, a cylindrical holding member having a transversal bottom face and a transversal top face, and an axial bore extending between said top face and said bottom face for receiving the neck portion of a container, said cylindrical holding member being formed with a cutout extending in the cylindrical outer surface thereof from said top face to said bottom face, said holding member being further formed with a groove in said bottom face thereof, said groove being concentric with said cylindrical surface; and a closure cap having a cylindrical wall and a transversal top wall, said closure cap having two diametrically located inwardly curved lugs projecting from the free edge of said cylindrical wall and engaging

said groove in a position of said closure cap in which said top wall thereof is adapted to abut against the end of the container neck portion passing through said axial bore, said closure cap being turnable on said holding member with said lugs sliding in said groove to a position in which one of said lugs registers with said cutout in said holding member, from which latter position said closure cap may be pivoted about a joint formed by the end portion of the other of said lugs and by said groove, said one of said lugs passing through said cutout during such opening pivoting movement.

2. A closure comprising in combination, a cylindrical holding member having a transversal bottom face and a transversal top face and formed with an axial bore extending between said top face and said bottom face for receiving the neck portion of a container, said cylindrical holding member being formed with a cutout extending through the cylindrical outer surface thereof from said top face to said bottom face, said holding member being further formed with a groove in said bottom face thereof, said groove being concentric with said cylindrical surface and having two ends opening into said cutout, said groove having two portions of varying depth, one of said portions of said groove gradually decreasing its depth from one of said ends of said groove, and the other portion of said groove gradually increasing its depth from the other of said ends of said groove; and a closure cap having a cylindrical wall and a transversal top wall, said closure cap having two diametrically located inwardly curved lugs projecting from the free edge of said cylindrical wall, each of said lugs engaging one of said portions of said groove in a position of said closure cap in which said top wall thereof is adapted to abut against the end of a container neck portion passing through said axial bore, said top wall of said closure cap moving towards said top face of said holding member while said closure cap is rotated in a direction causing movement of said lugs toward portions of decreased depth of said portions of said groove, said closure cap being turnable in a direction opposite to said direction to a pivoting position in which one of said lugs registers with said cutout in said holding member, from which pivoting position said closure cap may be pivoted about a joint formed by the end portion of the other of said lugs and by said groove, said one of said lugs passing through said cutout during such opening pivoting movement.

3. A closure comprising in combination, a cylindrical holding member having a transversal bottom face and a transversal top face and formed with an axial bore extending between said top face and said bottom face for receiving the neck portion of a container, said cylindrical holding member being formed with a cutout extending through the cylindrical outer surface from said top face to said bottom face, said holding member being further formed with a groove in said bottom face thereof, said groove being concentric with said cylindrical surface and having two ends opening into said cutout, said groove having two portions of varying depth, one of said portions of said groove gradually decreasing its depth from one of said ends of said groove, and the other portion of said groove gradually increasing its depth from the other of said ends of said groove; and a closure cap having a cylindrical wall and a transversal top wall, said closure cap having two diametrically located in-

wardly curved lugs projecting from the free edge of said cylindrical wall, each of said lugs engaging one of said portions of said groove in a position of said closure cap in which said top wall thereof is adapted to abut against the end of a container neck portion passing through said axial bore, said top wall of said closure cap moving towards said top face of said holding member while said closure cap is rotated in a direction causing movement of said lugs toward portions of decreased depth of said portions of said groove, said closure cap being turnable in a direction opposite to said direction to a pivoting position in which one of said lugs registers with said cutout in said holding member, from which pivoting position said closure cap may be pivoted about a joint formed by the end portion of the other of said lugs and by said groove, said one of said lugs passing through said cutout during such opening pivoting movement, said closure cap having an abutment on the outer surface of said cylindrical wall in the region of said other lug adapted to engage the container when said closure cap is pivoted to a wide open position.

4. A closure comprising in combination, a cylindrical holding member having a transversal bottom face and a transversal top face and formed with an axial bore extending between said top face and said bottom face for receiving the neck portion of a container, said cylindrical holding member being formed with a cutout extending through the cylindrical outer surface thereof from said top face to said bottom face, said holding member being further formed with a groove in said bottom face thereof, said groove being concentric with said cylindrical surface and having two ends opening into said cutout, said groove having two portions of varying depth, one of said portions of said groove gradually decreas-

ing its depth from one of said ends of said groove, and the other portion of said groove gradually increasing its depth from the other of said ends of said groove; and a closure cap having a cylindrical wall and a transversal top wall, said closure cap having two diametrically located inwardly curved lugs projecting from the free edge of said cylindrical wall, each of said lugs engaging one of said portions of said groove in a position of said closure cap in which said top wall thereof is adapted to abut against the end of a container neck portion passing through said axial bore, said top wall of said closure cap moving towards said top face of said holding member while said closure cap is rotated in a direction causing movement of said lugs toward portions of decreased depth of said portions of said groove, said closure cap being turnable in a direction opposite to said direction to a pivoting position in which one of said lugs registers with said cutout in said holding member, and the other of said lugs arrives at the point at which said other portion of said groove associated therewith meets said one portion of said groove, at which point said other of said lugs is prevented from further movement by the smaller depth of said one portion of said groove, from which pivoting position said closure cap may be pivoted about a joint formed by the end portion of the other of said lugs and by said groove, said one of said lugs passing through said cutout during such opening pivoting movement.
